CARBON PACK OR CONTAINER

Harry Landsiedel, Buffalo, N. Y., assignor to
Remington Rand Inc., Buffalo, N. Y., a corpora-
tion of Delaware

Application March 19, 1934, Serial No. 717,014

11 Claims. (Cl. 206—57)

This invention relates to packs or containers for loose sheets and more particularly to a sheet pick-up to facilitate the removal of the uppermost sheet upon opening the cover of the pack.

The difficulty in removing a single sheet of carbon paper, for example, from its container is well known. The sheets, being made of a thin tissue paper, are prone to adhere slightly to one another and hence it is difficult to remove one sheet alone without wrinkling or tearing it, defacing it in some manner or displacing other sheets in the pack. In addition to the difficulty arising from the fine texture of the paper itself, the carbon rubs off the sheet and soils the hands of the person removing it, and hence a task which ought to be a simple one becomes rather difficult and distasteful.

It is an object of my invention to overcome the aforementioned difficulties and make the task of removing a single sheet of paper from its pack a simple one.

Another object of my invention is to provide an improved pick-up member which is attached to the cover of the sheet container so that the mere raising of the cover will lift the uppermost sheet where it may be grasped easily.

A further object is to provide an improved pick-up member for a carbon sheet container to which the uppermost sheet in the pack will adhere when a slight pressure is applied to said pick-up member.

To the above and other ends which will hereinafter appear, my invention consists in the features of construction, arrangements of parts and combinations of devices set forth in the following specification and particularly pointed out in the appended claims.

In the drawings wherein like reference characters designate corresponding parts in the different views—

Fig. 1 is a perspective view of a common form of carbon sheet folder to which one form of my invention has been applied;

Fig. 2 is an enlarged, detail, fragmentary, vertical sectional view along the line 2—2 of Fig. 1 and looking in the direction of the arrows at said line, the view showing the normal relation of the carbon sheets; the folder and the pick-up member in a closed pack;

Fig. 3 is a like view of the same showing pressure being applied to the pick-up member;

Fig. 4 is a vertical sectional view similar to Fig. 2 showing the cover in a raised position with the uppermost carbon sheet adhering to the pick-up member;

Fig. 5 is an enlarged perspective view of a por-

tion of my device showing the pick-up member and cover leaf in disassembled relation;

Fig. 6 is an enlarged perspective view of a portion of a carbon pack to which another form of my invention has been applied;

Fig. 7 is a perspective view showing still another form of pick-up member applied to the box type of carbon sheet container; and

Figs. 8, 9 and 10 are enlarged, fragmentary, vertical cross sectional views of the same similar to Figs. 2, 3, and 4.

In Figs. 1—5 I have illustrated a construction embodying my invention applied to a common form of carbon sheet pack employed for holding a relatively small number of carbon sheets. This carbon pack comprises a plurality of carbon sheets 20 loosely disposed in a container or folder 21, said folder including an upper or cover leaf 22 and a lower or back leaf 23 hinged to the cover leaf 22 as at 24. In the cover leaf 22, preferably in the lower right-hand portion as viewed in Fig. 1 and near an edge thereof, is a cut or aperture 25 over which is mounted a disk or member 26 made of paper, thin celluloid, or any other suitable resilient material. Whatever size or shape the aperture 25 may assume, for example, a circular cut which could be approximately one-half inch in diameter, the resilient member 26 may be the same or any suitable shape, but it should be of such dimensions as will allow it to completely fill, 20 cover, extend across or underlie the aperture 25 and preferably overlap the edges thereof as shown in Figs. 2, 3, 4 and 7 to 10 inclusive.

On the underside of the disk 26 there is supplied a suitable pick-up means which may be in the form of a coating, film or layer of a pressure-sensitive, non-drying adhesive material as indicated at 27, said adhesive causing the disk to adhere to the surface of the cover in close proximity with the aperture 25. The adhesive used in 35 this connection is of such a character as to permit of many applications without losing its tacky surface, such as described in Patent No. 1,760,820 or Re. 17,760. This construction of the disk with its pressure-sensitive adhesive mounted 40 over the aperture embodies one form of my invention, and comprises what may be termed a "pick-up" means. I prefer to inscribe the word "Press" or some such indication on the upper non-coated side of the disk 26.

In addition to this construction of the adhesive coated disk member, it may be made by only applying the pressure-sensitive non-drying adhesive over that portion of the disk which registers with the aperture. Then the disk or resilient 45

member could be applied to the cover 22 by any suitable means such as a drying adhesive applied over those portions of the disk which came in contact with the cover. It will be observed that in the form of the invention shown in Figs. 1-5 the adhesive coating 27 is not normally in contact with the uppermost carbon sheet (Fig. 2) and does not touch said sheet until pressure is applied to the disk 26, to flex said disk through the aperture 25 as shown in Fig. 3. Thus, it will be apparent that the aperture 25 constitutes in effect a finger receiving aperture.

In operation, when it is desired to remove one of the carbon sheets 20 from the folder 21, illustrated in Figs. 1 to 5 inclusive, the operator applies a slight pressure to the disk 26, as by means of her index finger, as shown in Fig. 3. Previous to the application of pressure the parts occupy the relationship shown in Fig. 2, but when the index finger is applied to the disk 26, its resilience will allow it to be depressed (Fig. 3) through the finger receiving aperture 25, causing the pressure-sensitive non-drying adhesive 27, to come in contact with the uppermost carbon sheet 20. Only a slight pressure need be applied and the slight contact of the adhesive with the carbon sheet will make it adhere to the disk. The finger may then be removed and the cover raised, said cover now carrying along with it the lower right-hand corner portion of the uppermost sheet of carbon paper, as illustrated in Fig. 4. The cover is then lifted to a convenient height where the carbon sheet 20 can be grasped by the operator and removed with ease.

In the above described form of the invention, or in the form to be described hereinafter, the cover 22 may be equipped with a tab or lifting means 38, as illustrated in Fig. 6, to facilitate in raising the cover 22 after pressure has been applied at the point indicated by the term "Press" to bring about the adherence of the uppermost sheet to the pick-up means. If used in connection with the form of the invention shown in Figs. 1-5, an ear may be provided on the disk or resilient member 26 which will accomplish the same purpose. Otherwise the tab may comprise a small folded piece of suitable thin material which can be fastened to the cover in the proper place. In any form the tab 38 may be folded down to a position adjacent the cover leaf as indicated by the dotted line showing in Fig. 6. Such a folding action of the tab 38 will permit several carbon packs to be stacked one upon the other in close relation.

In Figs. 7, 8, 9 and 10 I have illustrated a construction embodying my invention applied to another type of carbon sheet pack which ordinarily will hold a considerably greater number of sheets than the above described folder packs. This form of pack comprises a plurality of carbon sheets 40 loosely disposed in a container 41, said container including a flanged bottom or tray member 42 and a split top member. The split top member comprises a front cover portion 43, to be hereinafter referred to as the "cover", hinged by means of a pliable strip 45 to a rear cover portion 44, said rear cover portion 44 being permanently secured to the tray member 42.

In one of the lower corners of the cover 43 (in the upper left as viewed in Fig. 7) is a finger receiving aperture 70 of suitable size and shape, for example a circular opening large enough to

admit a normal index finger across which is mounted a resilient supporting member or disk 71 secured to the cover by any suitable means, such as adhesive. The disk or member 71 may be made of any thin resilient material such as rubber for example, and may assume any shape which will allow it to extend across the aperture. Preferably disk or member 71 is large enough and resilient enough to allow it to be flexed so that its under side may touch the bottom of the container. With this end in view it may be found desirable to have the disk or member 71 somewhat larger than the aperture and secured to the under side of the cover 43 preferably only at its extreme edges, as indicated at 73 in Figs. 9 and 10. Such a construction will allow a maximum flexure of the disk 71.

On the under side of the disk or member 71 there is a pressure-sensitive pick-up means 74 which may be a small loop of tape coated with a non-drying adhesive as shown, or it may be merely a spot of the non-drying adhesive on the under side of said member. Whatever form it takes, the means 74 is of such a character as will allow it to adhere to the uppermost carbon sheet 40 in the pack when pressure is applied through the finger receiving aperture 70 to the member 71 as indicated in Fig. 9. Furthermore, it will be observed that the means 64 is normally in the position shown in Fig. 8 and not in contact with the uppermost carbon sheet. The operation of this form of my invention is directly similar to the previously described form shown in Figs. 1-5.

From the broader aspects of my invention when I refer herein to a container having a cover, this language is intended to apply to either the folder or box type of sheet pack.

From the foregoing description it will be apparent that a novel sheet pick-up means, for carbon packs, for example, has been provided which will greatly facilitate the removal of the carbon sheets from their containers.

Various changes may be made in the construction, and certain features thereof may be employed without others, without departing from my invention as it is defined in the accompanying claims.

What I claim as new and desire to secure by Letters Patent is:

1. A carbon pack comprising a container having a cover, a pack of loosely disposed carbon sheets in said container, an aperture in said cover, a resilient disk mounted over said aperture, and an adhesive applied over the entire under surface of said disk, whereby said adhesive performs the double function of securing the disk to the cover and acting as a pick-up means when pressure is applied to said resilient disk to bring it into contact with the uppermost sheet in the pack.

2. A container for loosely disposed sheets, said container having a cover with an aperture therein, and a resilient pick-up member larger than said aperture and having its marginal portions secured to the marginal portions of said cover around said aperture and having the intermediate portion thereof extending over said aperture, the resilience of the pick-up member being sufficient to allow it to be flexed for contact with the uppermost sheet.

3. A container for loosely disposed sheets, said container having a cover with an aperture therein, and a pick-up member of thin flexible sheet material larger than said aperture and having its marginal portions secured to the marginal

portions of said cover around said aperture, said member having a non-drying adhesive on the under side thereof.

4. A container for loosely disposed sheets, said container having a cover with an aperture therein, and a pick-up member of thin flexible sheet material larger than said aperture, and coated on the under side thereof with a non-drying adhesive, said pick-up member having its marginal portions secured to the marginal portions of the upper side of said cover around said aperture, whereby the thickness of said cover and the manner of mounting said pick-up member maintain the non-drying adhesive out of the plane of the under side of said cover.

5. A pack comprising a container, said container having a cover with an aperture therein, a pack of loosely disposed sheets in said container, and a resilient pick-up member larger than said aperture and having the marginal portions thereof secured to the marginal portions of said cover around said aperture and the intermediate portion thereof extending over said aperture, whereby the uppermost sheet in said container may be picked up when pressure is applied over said intermediate portion and the cover is raised.

6. A carbon pack comprising a container, said container having a cover with an aperture therein, a pack of loosely disposed carbon sheets in said container, a resilient member of thin, flexible sheet material larger than said aperture secured to said cover about the marginal portions of said aperture and having the intermediate portion thereof extending over said aperture, and pick-up means applied to the under side of the intermediate portion of said resilient member and due to the thickness of the cover and manner of mounting thereon being normally maintained out of contact with said carbon sheets, whereby upon the application of pressure to the upper side of said resilient member over the intermediate portion thereof, said member will be flexed to bring said pick-up means into contact with the uppermost carbon sheet causing it to adhere thereto.

7. A carbon pack comprising a container, said container having a cover with an aperture therein, a pack of loosely disposed carbon sheets in said container, a resilient member of thin flexible sheet material larger than said aperture and mounted over said aperture, and an adhesive applied on the under surface of said resilient member, said adhesive performing the double function of securing the resilient member to the cover about the marginal portions of the aperture and acting as a pick-up means when pressure is applied to said resilient member to flex it through said aperture and into contact with the uppermost sheet in the pack.

8. A carbon pack comprising a container, said container having a cover with an aperture therein, a pack of loosely disposed carbon sheets in said container, a disk of thin flexible sheet material larger than said aperture secured to the upper side of said cover over said aperture, the marginal portions of said disk engaging with the marginal portions of said cover around the aperture, and a non-drying adhesive on the exposed portion of the under side of said disk, said non-drying adhesive acting as a pick-up means which is normally maintained out of contact with the uppermost sheet in the pack due to the thickness of the cover and the manner of mounting said disk over said aperture, whereby upon the application of pressure to the upper side of said disk and over said adhesive the disk will be flexed to bring the adhesive into contact with the uppermost carbon sheet causing it to adhere thereto so that when the cover is raised said sheet will be lifted therewith.

9. A container for loosely disposed sheets, said container having a cover with a finger receiving aperture therein, a resilient member larger than said aperture carried by the cover in cooperative relation with said finger receiving aperture and which may be flexed downward relatively to the cover by a finger pressure exerted on the resilient member, and a non-drying adhesive carried by said resilient member and adapted to be forced into contact with the uppermost sheet in said container by a downward flexing of said member.

10. A container for loosely disposed sheets, said container having a cover with a finger receiving aperture therein, a resilient member larger than said aperture carried by said cover in cooperative relation with said finger receiving opening and having a pick-up means on the underside thereof, whereby when finger pressure is applied to said resilient member it will be flexed downward and will force said pick-up means into contact with the uppermost sheet in said container causing it to adhere thereto.

11. A container for loosely disposed sheets, said container having a cover with a finger receiving aperture therein, a resilient member larger than and in cooperative relation with said aperture, said resilient member being carried by the cover and which may be flexed downward relatively thereto by a finger pressure exerted on the resilient member, a non-drying adhesive carried by said resilient member and adapted to be forced into contact with the uppermost sheet in said container by a downward flexing of said member thereby causing said sheet to adhere thereto, and a tab carried by said cover to facilitate in the raising thereof so that said sheet may be removed.

HARRY LANDSIEDEL.
